Inventor

Leon J. Priebatsh

UNITED STATES PATENT OFFICE.

LEON J. PRIEBATSCH, OF BROOKHAVEN, MISSISSIPPI.

PLOW.

Application filed October 18, 1923. Serial No. 669,373.

To all whom it may concern:

Be it known that I, LEON J. PRIEBATSCH, a citizen of the United States, residing at Brookhaven, in the county of Lincoln and 5 State of Mississippi, have invented certain new and useful Improvements in Plows, of which the following is a specification.

This invention relates to improvements in plows.

10 An important object of the invention is to provide a plow of improved construction and whereby the beam and standard are separable.

15 A further object of the invention is to provide a plow in which parts may be replaced if worn or broken, without the expense of securing an entire new plow.

20 Other objects and advantages of this invention will be apparent during the course 25 of the following description.

In the accompanying drawing forming a part of this specification and in which like numerals are employed to designate like parts throughout the same:

Figure 1 is a side elevation of the assembled plow,

Figure 2 is a side elevation looking at the inside of the landside,

Figure 3 is a sectional view taken on line 30 3-3 of Figure 1, and

Figure 4 is a partial perspective view of the plow beam.

In the accompanying drawing, wherein for the purpose of illustration is shown the 35 preferred embodiment of my invention, the numeral 10 designates a plow beam of commonly used construction, the lower extremity thereof carrying a projecting lug 11 for engagement with a standard. A 40 usual form of standard 12 has a rectangular opening 13 formed therein for engaging the lug 11, a right-angled bracing shoulder 14 being formed on said standard below the opening 13. The standard 12 also is provided with bolt holes 15 which receive the 45 bolts for securing the plow beam. The inner face of the landside is cut away as at 16 to receive a handle beam 17, a bolt hole 18 being drilled therein for the purpose of securing 50 the handle beam to the standard.

In assembling the device, the plow beam

10 is positioned against the bracing shoulder 14 and the lug 11 fitted into the opening 13. A pair of bolts 19 are then inserted through 55 the openings 20 in the plow beam and openings 15 in the standard, the nuts 21 being tightened and the beam being securely fastened in place. Upon the beam becoming broken or perhaps some part of the standard, it is obvious that the device may be 60 quickly and easily taken apart or assembled.

It is to be understood that the form of my invention herewith shown and described is to be taken as the preferred example of 65 the same, and that various changes in the shape, size, and arrangement of parts may be resorted to without departing from the spirit of my invention or the scope of the subjoined claims.

Having thus described my invention, I 70 claim:

1. A device of the character described comprising the combination of a plow beam having a projecting lug formed on the lower extremity thereof, and a standard having a 75 rectangular opening formed therein, a bracing shoulder formed thereon, and means for securing the beam to the standard.

2. The combination of a plow beam, a projecting lug formed on said plow beam, a 80 standard having a rectangular opening for receiving the beam lug, a bracing shoulder for strengthening the connection of the plow beam and standard, a plurality of bolt holes formed in the standard, and bolts for securing the plow beam to the standard.

3. The combination of a plow beam, a projecting lug formed on said plow beam, a standard having a receiving portion formed therein for receiving the said lug, 90 a bracing shoulder formed on the standard, and means for rigidly securing the plow beam to the standard.

4. The combination with a plow beam, a projecting lug formed on one side of the 95 plow beam, and a standard having an opening therein for receiving the projecting lug, means formed on the standard for bracing the beam, and a plurality of bolts and nuts for securing the beam to the standard.

5. The combination with a plow beam, a 100 tapered lug formed on one side of the plow

beam, a standard having a tapered opening formed therein for receiving the projecting lug, a right-angled shoulder formed on the standard for supporting the plow beam, bolt 5 holes formed in the standard, and a plurality of bolts for securing the plow beam to the standard.

In testimony whereof, I have affixed my signature in the presence of two witnesses.

LEON J. PRIEBATSCH.

Witnesses:
